OLIVER PERRY, WILLIAM N. WELLES, AND CLARK PERRY, OF ORTONVILLE, MICHIGAN.

Letters Patent No. 64,359, dated April 30, 1867.

IMPROVEMENT IN SHEEP-SHEARING TABLE.

The Schedule referred to in these Letters Patent and making part of the same.

TO ALL WHOM IT MAY CONCERN:

Be it known that we, OLIVER PERRY, WILLIAM N. WELLES, and CLARK PERRY, of Ortonville, in the county of Oakland, and in the State of Michigan, have invented certain new and useful Improvements in Sheep-Shearing Tables; and do hereby declare that the following is a full, clear, and exact description thereof, reference being had to the accompanying drawings, and to the letters of reference marked thereon, making a part of this specification.

Figure 1 represents a side elevation.

Figure 2, an end view.

Our invention consists in the construction of a table whereon the sheep are placed and sheared in a short space of time, and whereby the wool is collected without becoming admixed with foreign substances. This table is usually constructed about three feet in height, with its top about four feet in width, but we do not wish to be understood as confining ourselves to any particular size.

In the annexed drawings, A is the top of the table, which is supported by four or more uprights *a a*, with cross and side braces *b b*. The braces *a a* are placed at an angle from the top A, so that a suitable and substantial base is formed for the table. At each side of the table A are pivoted near its end two swinging frames *d d*, having slanting tops *B B'*, which are adjusted to the main top A by means of cords *g g*, and operated by the treadle C. This treadle is pivoted to the lower part of one of the stays, *e*, and extends across to the front of the frame, where there is a ratchet, *x*, placed in a vertical position on the opposite stay, *e*. It will be seen that the treadle passes over the cord *g*, which is attached to one of the centre stays *d* of the swinging frames, and when said treadle is brought down and caught into the ratchet *x* the two tops *B B'* are flush against the sides of the top A, and form the table upon which the sheep are to be placed. The tops *A B B'* are made slightly concave in their centres to conform to the shape of the sheep and to more effectually secure them thereon. The sheep to be sheared is placed upon the table with its head and fore feet under the strap *i*, and with hind feet secured in the loops *m n*, when its feet, belly, and neck are sheared and the wool caught in a bag at the side of the table. The sheep is then turned and sheared upon its side. After shearing these portions, the treadle is uncaught from the ratchet and the frames *d d'* allowed to swing apart from the top A as seen in red lines fig. 1, when the sheep is turned with its back up and feet between the frames, with head under the loop *i*; the back is then sheared and wool caught as before, when the frames are allowed to separate and the sheep taken from the table. This invention secures the sheep in such a manner as to allow the operator to perform his work in less time, and to do it more effectually than it has heretofore been accomplished.

Having thus fully described our invention, what we claim as new, and desire to secure by Letters Patent, is—

The combination and arrangement of the table A, swinging frames *B B'*, rope *g*, and treadle C, all constructed and operating in the manner substantially as and for the purposes herein specified.

In testimony that we claim the foregoing we have hereunto set our hands and seals this 23d day of February, 1867.

OLIVER PERRY, [L. S.]
